UNITED STATES PATENT OFFICE

RALPH W. DOEG, OF DETROIT, MICHIGAN, ASSIGNOR TO KELVINATOR CORPORATION, OF DETROIT, MICHIGAN, A CORPORATION OF MICHIGAN

COMPRESSOR VALVE

Application filed December 16, 1927. Serial No. 240,407.

My invention relates generally to fluid compressors and it has particular relation to a novel type of compressor discharge valve. Heretofore, it has been customary to provide fluid compressors with discharge valves in which a single valve closing member moves to various heights to provide various sizes of openings for the escape of the compressed fluid depending upon the volume of the charge within the cylinder. By my invention I have provided a movable valve closing member which moves only when an excessive charge of compressed fluid is contained within the cylinder and which is provided with additional means for permitting the escape of the compressed fluid under normal conditions without necessitating movement of said valve closing member.

One object of my invention is to provide a novel type of discharge valve for compressors.

Another object of my invention consists in providing a novel type of discharge valve comprising a complete valve mechanism mounted on a valve closing member.

A further object of my invention is to provide a main discharge valve which moves only when an excessive charge of compressed fluid is contained within the cylinder and a smaller valve of relatively light weight and substantially noiseless adapted to be actuated when a normal charge of compressed fluid is contained therein.

For a better understanding of my invention reference may now be had to the accompanying drawings of which

Fig. 1 is a vertical cross-sectional view of a two cylinder compressor provided with discharge valves constructed in accordance with my invention.

Fig. 2 is a plan view of the structure illustrated in Fig. 1.

Fig. 3 is a bottom plan view of the valve closing member of the main discharge valve.

In the drawings I have shown a double cylinder block 10 provided with pistons 11 and 12. The top of the cylinder block 10 is closed by means of a cylinder head 13, containing an opening 14 opposite each cylinder, and set cured thereto by means of bolts 15. Each

piston 11 and 12 is provided with an opening 16 in the top thereof, which is closed by means of a valve member 17, movable with respect to the piston but mounted thereon. Fluid to be compressed is drawn from the crankcase (not shown) of the compressor, through the piston and through the valve port 16 when the valve 17 is in its open position, thus admitting the charge to be compressed into the cylinder.

Each of the openings 14 is provided, at its lower edge with an annular inwardly projecting edge 20 which serves as a valve seat. Disposed within each of the openings 14 is a hollow member 21, of substantially cup shape, having an inclined lower outer edge 22, side walls 23 and a bottom surface 24. The bottom surface 24 is provided with a plurality of circumferentially arranged openings 25 extending therethrough. These openings 25 are closed by means of a thin flexible disk 26, which is held in resilient engagement with the inner surface of the bottom wall 24 by means of a relatively light helical compression spring 27. The spring 27 is retained 70 concentrically disposed with respect to the disk 26 by means of an annular member 28, which is provided with a downwardly extending portion 29, disposed within the spring 27, the bottom of which serves as an 75 abutment for the disk 26. The member 28 is also provided with a circumferential flange 30 which rests on top of the cup shaped member 21 and retains the spring 27 under pressure. The member 28 is provided with openings 31 for the passage of gas therethrough.

The member 28 is maintained in engagement with the top of the member 21, against the action of the spring 27 by means of a relatively stronger spring 32, which, in turn is held in position by means of a top or cap member 33, which is provided with a centrally disposed opening 34 to permit the passage of gas therethrough. The cap member 33 rests, or is held, in an annular groove in the cylinder head 13, surrounding the opening 14, by means of a clamping member 36 provided with bifurcated end portions 37 which span the upper portions and engage the lower portions of the cap members 33. The member 36

is held in clamping engagement with the members 33 by means of a bolt 38 which passes through an opening 39 adjacent the center thereof and is rigidly secured to the cylinder head 13.

During the operation of the compressor the piston compresses the gas within the cylinder, which has previously been drawn through the piston valve port 16. If the charge within the cylinder is normal in volume the pressure of the gas, as the piston approaches the upper end of its stroke, is sufficient to raise the disk 26, against the action of the spring 27, into engagement with the bottom of the member 29, thus uncovering the many small valve ports 25. The gas compressed within the cylinder 10 thereupon passes through the openings 25 in the member 21, through the openings 31 in the member 28 and through the opening 34 in the member 33, from which it passes into any suitable tank or reservoir (not shown). As soon as the gas has been discharged from the cylinder 10 the spring 27 moves the disk 26 back to its normal position, thus closing the openings 25 as the piston begins its downward stroke. The fact that the disk 26 is relatively light in weight renders it substantially noiseless in operation.

If the charge of compressed gas in the cylinder 10 is unusually large, or if a quantity of oil in liquid form is contained therein, the opening of the valve ports 25 will not provide a sufficiently quick relief and the pressure in the cylinder builds up. When this occurs the pressure in the cylinder soon becomes sufficiently high to raise the member 21, and with it the members 26, 27 and 28, against the action of the spring 32, thus opening the main valve ports 14 and permitting the gas and oil to pass, in addition to the pathway through the valve ports previously discussed, through the main ports 14 and through laterally disposed passageways 35 provided in the cylinder head 13, and thence into any suitable receptacle (not shown). As soon as the pressure within the cylinder is restored to a normal value the spring 32 moves the member 21 again into engagement with the seat 22, thus closing the main port 14, and the gas continues to escape through the openings 25 until the pressure thereof has reached a much lower value, as previously described.

Although I have illustrated but one form of my invention and have described in detail but a single application thereof, it will be apparent to those skilled in the art that it is not so limited but that various modifications and changes may be made therein without departing from the spirit of my invention or from the scope of the appended claims.

What I claim is:

1. A compressor valve mechanism comprising a member provided with a valve port, a

relatively movable member of substantially cup shape adapted to close said port and provided with relatively smaller valve ports in the base thereof, means disposed within said cup-shape member adapted to close said ports, 70 an abutment member movably supported relatively to said cup-shape member and adapted to engage the upper edge of said cup-shape member and provided with a portion extending into proximity to said valve port closing means, a relatively weak spring disposed between said abutment member and said valve port closing means, a relatively strong spring adapted to engage said abutment member and adapted to hold it in resilient engagement with said cup-shape member, and means for holding said relatively strong spring in position.

2. A compressor valve mechanism comprising a cylinder head provided with an aperture therethrough having a constricted portion adjacent one end thereof constituting a valve seat, a cup-shape member disposed within said aperture engaging said seat and provided with a plurality of valve ports in the base thereof, a movable member disposed within said cup-shape member and adapted to close the ports therein, an abutment member disposed within said aperture in engagement with the upper edge of said cup-shape member and having a portion extending thereinto in spaced relation with said port closing member, a relatively weak spring disposed within said cup-shape member between said abutment member and said port closing member, a cage secured adjacent the end of the aperture opposite the constricted portion, and a relatively strong spring secured within said cage and engaging said abutment member.

In testimony whereof I hereunto affix my signature.

RALPH W. DOEG.
